UNITED STATES PATENT OFFICE.

LOUIS VINGHEROETS, OF GRAND RAPIDS, MICHIGAN.

TOOL.

Application filed August 21, 1923. Serial No. 658,621.

This invention appertains to vital improvements in tools and the primary object of the invention is to provide a simple tool, which will readily and quickly extract or 5 insert a bushing in a bearing, with a minimum amount of labor, and without injury to the bushing.

A further prime object of the invention is the provision of a tool for extracting and 10 replacing bushings in bearings which embodies novel means for engaging the bushing, novel means for engaging the bearing, and means for connecting the bushing and bearing means together for effectively with- 15 drawing or placing a bushing in position.

A still further object of the invention is to provide an improved tool of the above character, which will be durable and efficient in use, one that will be simple and easy to 20 manufacture and one which can be placed upon the market at a small cost.

With these and other objects in view, the invention consists in the novel construction, arrangement and formation of parts, as will 25 be hereinafter more specifically described, claimed and illustrated in the accompanying drawings, in which drawings:

Figure 1 is a longitudinal sectional view through the tool showing the same arranged for extracting a bushing from a bearing.

Figure 2 is a top plan view of the tool.

Figure 3 is a transverse section through the tool taken on the line 3—3 of Figure 1.

Figure 4 is a bottom plan view of the tool.

Figure 5 is a diametric section through a portion of the tool utilized for engaging a bushing, when the tool is utilized for forcing a bushing into place, and

Figure 6 is a diametric section through the means for engaging the bearing, when the tool is used for forcing a bushing into place.

Figure 7 is a side elevation of a tool partially in section showing the same in position for extracting a bushing, and

Figure 8 is a similar view of the device shown in the operation of inserting a bushing.

Referring to the drawings in detail, 50 wherein similar reference characters designate corresponding parts throughout the several views, the letter A generally indicates the improved tool, which comprises a longitudinally extending bolt 10 having one end thereof provided with male threads 11 and its intermediate portion provided with

a smooth bearing surface 12. The end of the bolt 10 opposite to the end provided with threads 11 can be provided with a reduced polygonal extension 13 for permitting the 60 bolt to be engaged by a wrench to prevent the turning of the bolt. The smooth portion 12 of the bolt 10 adjacent to the polygonal extension 13 is provided with an annular groove 14, the purpose of which, will 65 be hereinafter more fully described.

Threaded upon the threaded end 11 of the bolt 10 is a relatively large manipulating nut 15 including the polygonal head portion 16 and a reduced axial extension or guide 17. 70

A guide sleeve 18 for the bushing and for engaging the bearing is provided for receiving the bolt 10 and this sleeve is provided at its outer end with an internal shoulder 19 for engaging the cylindrical extension 75 or guide 17 on the nut 15. A suitable thrust bearing 20 is adapted to be interposed between the polygonal head 16 of the nut and the inner end of the sleeve 18 and this thrust bearing can be held in place on the extension 80 17 in any preferred way, such as by a ring 21 or by forming shoulders directly on the extension.

An annular member 22 is provided for engaging the bushing, when the tool is to be 85 used for extracting bushings from bearings and this member 22 is held in place by a suitable split annular retaining ring 23 having a reduced neck opening 24 for permitting the slipping of the ring in place in the 90 groove portion 14 of the bolt 10. This ring 23 is provided with a reduced extension 25 for fitting into the bushing engaging member 22.

When the tool is to be used for extracting bushings the smooth portion of the bolt 12 is slipped through the bushing and the inner end of the sleeve 18 is placed in engagement with the bearing. The bushing engaging member 22 is now slipped on the bolt 12 and held in place by the ring 23. The nut 15 is now rotated by a suitable wrench or the like which can be placed in engagement with the polygonal head 16 of the nut. This nut is now rotated in such a manner as to draw the 100 bolt 10 inwardly, which will force the member 22 into contact with the bushing and gradually draw the bushing from out of the bearing and into the sleeve 18.

When it is desired to use the tool for 110 placing bushings in place, the member 22 and the sleeve 18 are removed from the

2

bolt 10. A bushing engaging member 26 is substituted for the sleeve 18 and the same includes an annular body for receiving the guide or extension 17 on the nut 15 and the bore of the body is provided with a groove 27 for receiving the retaining ring 21 or the shoulders for holding the thrust bearing 20 in place. The bushing engaging member 22 is also removed from the bolt 10 and an enlarged annular bearing engaging member 30 is substituted therefor. This bearing engaging member 30 is provided with a bore 31 for permitting the same to be slipped upon the bolt 10 and this bearing engaging member 30 is held in place by the retaining ring 23, in the same manner as the member 22.

In use of the tool for pushing bearings in place, the member 26 is placed on the extension 17 and the bolt 10 is then slipped through the bearing, the bushing having been placed on the bolt in intimate contact with the member 26. The bearing engaging member 30 is now placed on the bolt and held in place by the ring 23. The nut 15 is rotated by a suitable wrench, and the member 26 engaging the bushing will effectively force the same in place. If the bolt 10 has a tendency to rotate with the nut 15, the bolt can be held against rotation by placing a suitable wrench on the polygonal extension 13 of the bolt.

From the foregoing description, it can be seen that I have provided an exceptionally simple and durable tool for effectively extracting bushings from bearings and for placing bushings in bearings which will not injure the bushings in any way whatsoever.

Changes in details may be made without departing from the spirit or the scope of this invention.

What I claim as new is:

1. A device for inserting and extracting bushings including a bolt having a reduced shank and screw threaded on one extremity, a nut threadedly mounted upon the said extremity, a thrust member including a collar rotatably mounted on the said nut and a sleeve for engaging a bearing, means for reducing the frictional contact between the said thrust member and nut, an annular bushing engaging member positioned upon the opposite extremity of the said bolt, and a retaining ring provided with a slot adapted to engage said reduced shank and prevent displacement of the annular engaging member.

2. A device of the class described including a longitudinal bolt having a reduced portion and screw threaded at one portion, a nut threadedly mounted on the said bolt

provided with a sleeve, a disc shaped thrust member rotatably mounted upon the said guide sleeve, anti-friction bearing members mounted between the said thrust member and nut, an annular bushing engaging member adapted to engage the opposite extremity of the bolt, and a slotted ring adapted to engage said reduced portion, and means for retaining the said bolt against rotation.

3. A tool of the class described comprising a guide sleeve having an interior shoulder formed at one end, a threaded bolt longitudinally movable through the said sleeve, an actuating nut threadedly engageable with the bolt including a polygonal wrench receiving head adapted to bear against the adjacent end of the guide sleeve and a cylindrical extension inserted through the shoulder of the guide sleeve, and a thrust bearing detachably mounted on the opposite end of the bolt.

4. A tool of the class described comprising a guide sleeve having an interiorly projecting shoulder formed in one end thereof, a threaded bolt longitudinally movable through the said guide sleeve and shoulder, an actuating nut threadedly engageable with the bolt including a polygonal wrench receiving head adapted to bear against the adjacent end of the guide sleeve and a reduced cylindrical extension rotatably fitted within the shoulder of the guide sleeve, and a thrust bearing detachably mounted on the opposite end of the bolt.

5. In a tool of the class described including a thrust sleeve, a bolt movable longitudinally through the said sleeve, a nut threaded on the bolt having a cylindrical extension projecting through the adjacent portion of the sleeve, a continuous thrust bearing slidably mounted on the opposite end of the bolt, and a retaining member detachably engageable with the bolt adapted to maintain the continuous thrust member in position.

6. A tool of the class described comprising a thrust sleeve, a bolt longitudinally movable through the sleeve, threaded on one end and having an annular groove formed adjacent its opposite end, an actuating nut threaded on the bolt having a reduced projection engageable with the sleeve, a continuous annular thrust bearing slidably fitted over the opposite end of the bolt, and a retaining ring having a slot formed therein adapted to slidably engage the reduced portion of the bolt to retain the annular thrust member in position.

In testimony whereof I affix my signature.

LOUIS VINGHEROETS
